UNITED STATES PATENT OFFICE.

JAMES HOULEHAN, OF CHICAGO, ILLINOIS, ASSIGNOR, BY DIRECT AND MESNE ASSIGNMENTS, TO THE HOULEHAN MAGNETIC SEPARATOR COMPANY, OF SAME PLACE.

ELECTROMAGNET.

SPECIFICATION forming part of Letters Patent No. 554,821, dated February 18, 1896.

Application filed May 10, 1895. Serial No. 548,843. (No model.)

To all whom it may concern:

Be it known that I, JAMES HOULEHAN, a citizen of the United States, residing at Chicago, in the county of Cook and State of Illinois, have invented a new and useful Improvement in Electromagnets, of which the following is a specification.

My invention relates to an improved electromagnet for use, particularly, in magnetic ore-separators, though it is also useful for separating magnetic from non-magnetic metals.

The primary object of my invention is to provide a construction of electromagnet whereby dead-centers or "zero-points" on the pole-pieces shall be prevented and thus enable the pole-pieces to be magnetized, even uniformly, throughout their surface.

To accomplish the object of my invention I preferably wind the magnet-cores which project from a central hub in a particular manner and connect the windings in multiple series with a suitable generator, and I form the pole-pieces in a circle, and, as an essential feature of my improvement, in alternating connected sections of soft iron and non-magnetic material, to the former of which alternate cores of the magnet lead, while the intermediate cores should straddle, at their ends, the junction-line between adjacent pole-

30 pieces of soft iron and non-magnetic material. By the construction thus generally outlined I attain diffusion of the generated magnetism over the entire surface of the annulus afforded by the alternate pole-piece sections 35 thereof of soft iron and non-magnetic material and thus avoid any zero-point thereon.

Referring to the accompanying drawings, Figure 1 shows my improved electromagnet by a view in end elevation, and Fig. 2 is a 40 diagrammatic view illustrating the manner I observe in winding each core.

A is a hub of soft (preferably gray) iron having radiating or extending outward from its circumference cores r and r' of the same 45 material, shown as eight in number, though the number may be varied without departure from my invention. The hub and cores may be cast in one piece. I wind the cores with insulated wire, (I have generally used No. 20 50 wire,) as follows: Beginning with the core r

at x I wind it helically in one direction nearly to its outer end, as indicated at w in Fig. 2; thence I carry the wire, outside the first winding, lengthwise of the core back, as indicated at s , to the starting-point, from which 55 another layer is wound, as indicated at w' , upon the first in the same direction as the latter nearly to the outer end of the core, from which the wire is carried back across the second layer lengthwise of the core, as indicated 60 at s' , to the starting-point. In the same manner the layers are wound in desired number according to the efficiency required—say one hundred and ten volts and fifteen ampères. The end of the last layer, which is also brought 65 back to the starting-point, is then carried to the inner end of the next adjacent core r' , about which it is wound in layers in the manner described of the preceding core, and thus each core is wound with wire and formed into 70 a spool B, the windings being connected in multiple series, as represented, and the end t of the wire from the last-wound core r' being directed through an opening v in the center of the hub, through which the initial end 75 t is also passed, and at which ends connection may be made with a suitable electric generator, (not shown,) as with the brushes of a series-wound dynamo-electric machine.

C' and C^2 are segmental pole-pieces formed, 80 respectively, of soft (preferably gray) iron and non-magnetic material, as zinc, which is the material I employ for the pole-pieces C^2 . The segmental pole-pieces are connected together end to end to form an annulus C , the 85 adjacent ends being preferably provided, as the means of intimately joining them, respectively, with tongues p and grooves p' , which fit each other.

Each core r extends to a different pole-piece 90 C' , preferably at a point about midway between its ends, where it is fastened, as by means of a screw o passing through the pole-piece, into the end of the core. Each core r' extends and is fastened like each core r to a 95 different pole-piece C^2 ; but to attain the best results of my improved construction each core r' should overlap at its extremity the line of junction between the adjacent pole-pieces, so as to cause, say, one-fourth of the 100

surface of the core end to contact with a pole-piece C' and the remainder thereof to contact with a pole-piece C^2 . To render this straddling of the pole-piece junction-lines by the 5 cores r' conveniently possible I cast the body of the magnet so as to have the cores r and r' in pairs with their respective members adequately close together, as shown.

I show my improved electromagnet in the 10 form of a wheel, because it is intended to be rotated in use and because the wheel form is preferred; but I do not limit my invention to the wheel form of the magnet.

What I claim as new, and desire to secure 15 by Letters Patent, is—

1. An electromagnet comprising a set of wire-wound soft-iron cores, and pole-pieces, successively of opposite polarities, at the outer 20 ends of said cores, said pole-pieces comprising segments joined together end to end and forming an annulus, said segments being composed alternately of soft iron and non-magnetic solid material, substantially as described.
- 25 2. An electromagnet comprising a set of wire-wound soft-iron cores terminating in pole-pieces, said pole-pieces being endlessly joined together and formed, respectively, of soft iron and non-magnetic material, the core 30 for each soft-iron pole-piece joining said pole-piece at a point between the pole-piece ends, and the core for each pole-piece of non-magnetic material straddling the junction-line between the latter and the adjacent soft-iron 35 pole-piece, substantially as described.

3. An electromagnet comprising a set of spools terminating in pole-pieces endlessly joined together and formed, respectively, of soft iron and non-magnetic material, each

spool comprising a soft-iron core wound with 40 layers of insulated wire, said layers being wound in parallel relation one upon the other each from a point on the cord toward the outer end thereof and connected in succession by the wire of each being extended back across 45 the layer lengthwise of the core from the outer end of the winding to the starting-point thereof, said spools being suitably connected, the core for each soft-iron pole-piece joining said pole-piece at a point between the pole-piece 50 ends, and the core for each pole-piece of non-magnetic material straddling the junction-line between the latter and the adjacent soft-iron pole-piece, substantially as described.

4. An electromagnet comprising a soft-iron 55 hub A having extending from it soft-iron cores r and r' each wound with layers of insulated wire, said layers being wound in parallel relation one upon the other each from a point on the core toward the outer end thereof and 60 connected in succession by the wire of each being extended back across the layer lengthwise of the core from the outer end of the winding to the starting-point thereof, said 65 windings being suitably connected from core to core, and an annulus C formed in sections C' and C^2 joined at their ends and comprising pole-pieces formed, respectively, of soft iron and non-magnetic material, as zinc, each core r joining a pole-piece C' between its ends, and 70 each core r' joining a pair of said pole-pieces C' and C^2 at their junction-line to straddle the latter, substantially as described.

JAMES HOULEHAN.
